UNITED STATES PATENT OFFICE.

SIMON ANDUAGA, JR., AND JUAN LUEVANO, OF MEXICO, MEXICO.

LIFE-SAVING APPARATUS FOR ELEVATORS AND CAGES.

Application filed March 21, 1921. Serial No. 453,904.

To all whom it may concern:

Be it known that we, SIMON ANDUAGA, Jr., mining engineer, and JUAN LUEVANO, mechanic, citizens of Mexico, residing at the city of Mexico, Federal District, Republic of Mexico, have invented certain new and useful Improvements in Life-Saving Apparatus for Elevators and Cages, of which the following is a specification.

10 This invention relates to safety suspending gear for elevators and the like particularly though not exclusively for use in mines and other places where a quick acting and sure supporting means for the elevators or 15 cage is essential to the safety of the passengers in preventing the falling of the elevator in the event of breakage of the usual suspension cable, or other accident.

Safety gear for the purpose aforesaid has 20 been devised hitherto consisting of a drawbar, block, or similar member movable relatively to the elevator or cage and to which the hoisting tackle is attached and arms or bars located in proximity to the elevator 25 guide posts and connected either directly to the drawbar or block, or to a link or member attached thereto. In the event of the breakage in the hoisting tackle, the drawbar or block and the member attached thereto, 30 when such is provided, falls, whereupon the ends of the arms or bars are caused to penetrate into the guide posts or engage with rackways thereon, or where such ends are specially formed these grip guide ropes. 35 Usually springs or weights, or both, are combined with the drawbar or its attendant link, if such is provided, in order to accelerate the operation of the gear. In some cases a compression spring is used and coiled 40 around the drawbar or a plurality of such are suitably arranged in connection with the aforesaid arms. In other constructions a tension spring is used attached at one end to the drawbar or block, and at the other to a 45 fixed part of the elevator or cage.

The object of the present invention is to improve safety suspending gear of the type aforesaid to render such gear more efficient and sure, a further object being to provide 50 means to protect the mechanism from dust, mud, pebbles, splinters of timber, and the like all of which are frequently the cause of the mechanism not operating efficiently or at all at the crucial moment.

55 According to the present invention the

safety suspension gear comprises a cross bar or equivalent device freely movable on guide rods and attached to a rod connected with the usual hoisting tackle, being normally held raised thereby, the said guide rods having means to limit the upward movement of the bar, arms or sprags pivotally mounted in the said bar, and a series of springs combined with the bar in such a manner that one of them is normally held in compression while the others are normally held in tension, so that in the event of a breakage in the hoisting tackle the cross bar falls instantaneously under the influence of the springs and its own weight whereupon the aforesaid arms or sprags are forcibly projected into the elevator guide posts. Means are also provided to prevent the wooden guide posts for the elevator from splitting when penetrated by the arms or sprags.

In the accompanying drawing, Fig. 1 represents a longitudinal cross-section of the mechanism, attached to a cage or elevator; and Fig. 2 is a sectional plan view of the apparatus on line 1—1 of Fig. 1.

With reference to the drawing, A is a housing, strongly connected to the top of the cage B by bolts or rivets C with the stopping mechanism mounted therein, independent of the elevator or cage. To the body D of this mechanism is connected the stem E to which the elevator or cage is suspended by the eye or hook F for the cable. The body D is guided on rods G which are fastened solidly to the housing and have widening at G' to restrain the body D from going up more than is convenient, when the elevator is in movement as it would not be convenient that the body D should go too far up, because the arms or sprags I which are located at each end of the body would get out of their place and thus give no efficiency.

The stem E forms seat for the spring K which compresses when the cage or elevator is suspended, until the body D rests at the points G' of the rods G, this position of course is adjusted beforehand so that the arms I in a critical moment are forced by springs L and the weight of the body D to enter the wooden-guides M for the elevator. In other words, the object of the springs K and L is to accelerate or enforce the descent of the body D, as the descent of this part must be instantaneous and with sufficient force so that the arms I get into the wooden-

guides M before the live force generated by the fall of the cage surpasses the resistance of the arms I or the wood in which they are going to rest.

5 However, if the strength of the springs would be wasted this is no obstacle for the apparatus not to function because the weight of the body D and that of the hook F with its stem E are sufficient to make the life-saving apparatus work.

As will be seen the whole mechanism is mounted inside the housing so that no dust, mud, pebbles, etc. which always are found in mine shafts, can enter. The arms I are 15 only permitted to enter the wooden guides through a hole in the U-iron N, this U-iron being jointed to the housing in such a way to prevent introduction of strange objects into its springs or articulations, and to protect 20 the wooden-guides from splitting when the arms I grasp into them.

The working of the apparatus will be readily understood by the following explanation: If the elevator or cage is suspended 25 the springs L will be in tension and the spring K in compression, so that in case a descent takes place by breaking of the cable or of the gyves or hooks, the springs take their normal position and force the 30 arms I into the wooden-guides in the shaft, and thus stopping the cage or elevator, preventing by this way the fall of the cage or elevator. The heavier the weight of the cage is, the stronger will it incline the arms to 35 grasp into the wood, and the security of sustaining the cage increases thereby.

As the arms I are working independent of each other in the arrangement we have designed, it will be seen that even when one 40 of these is rendered useless the apparatus can work with only one fluke as has been proved by several tests made.

We know that there have been granted several patents for life savers of different kinds for the purpose indicated, but our 45 mechanism shows essential differences from the hitherto known, and we wish it to be understood that various changes can be made in the details of the construction of the apparatus, for instance by employing 50 four rods G as shown by dotted lines in Fig. 2, and we do not wish to be limited to the precise construction shown, as variations may be made without departing from the spirit and scope of our invention. 55

Having thus described our invention, what we claim as new and desire to secure by Letters Patent is as follows:—

Life saving apparatus for elevators comprising a cross-bar freely movable on guide-rods and attached to a rod connected with the usual hoisting tackle, being normally held raised thereby, the said guide rods having means to limit the upward movement of the bar, arms pivotally mounted in the said bar, and a series of springs combined with the bar in such a manner that one of them is normally held in compression while the others are normally held in tension, so that in the event of a breakage in the hoisting 65 tackle the cross-bar falls instantaneously under the influence of the springs and its own weight whereupon the aforesaid arms are 70 forcibly projected into the elevator guide posts, and means to prevent the guide posts from spreading transversely when the arms 75 penetrate into them.

In testimony whereof we affix our signatures.

SIMON ANDUAGA (JUNIOR).
JUAN LUEVANO.
